We claim the ornamental design for a jug, as shown and described.

DESCRIPTION

FIG. 1 is a left side view of a jug according to the present invention;

FIG. 2 is a right side view of the jug seen in FIG. 1;

FIG. 3 is a front view of the jug seen in FIG. 1;

FIG. 4 is a rear view of the jug seen in FIG. 1;

FIG. 5 is a top view of the jug seen in FIG. 1; and,

FIG. 6 is a bottom view of the jug seen in FIG. 1.

The broken lines in the drawings illustrate the portions of the jug that form no part of the claimed design.

Shade lines having a combination of long and short lines in the drawings show contour and not surface ornamentation.
